J. C. KARNES

FIRE CONTROL SYSTEM FOR GUNS

Filed Feb. 26, 1927

UNITED STATES PATENT OFFICE.

JAMES C. KARNES, OF BUFFALO, NEW YORK.

FIRE-CONTROL SYSTEM FOR GUNS.

Application filed February 26, 1927. Serial No. 171,353.

(GRANTED UNDER THE ACT OF MARCH 3, 1883; 22 STAT. L. 625.)

The invention described herein may be used by the Government, or any of its officers or employees in prosecution of work for the Government, or by any other person in the 5 United States, without payment to me of any royalty thereon, in accordance with the act of March 3, 1883.

This invention relates to a fire control system for guns.

10 In firing at rapidly moving aerial targets it is necessary in order to insure a reasonable degree of accuracy that the dead time of maneuver be reduced to a minimum. Accordingly I have shown in Patent No. 15 1,555,061, mechanism for simultaneously setting the fuse of a projectile within a gun and firing the round.

However, in order that the projectile will be exploded at the predicted future position 20 for which the fuse range was calculated it is essential that the gun be correctly laid in azimuth and elevation at the instant of firing.

The principal object of this invention 25 then is to synchronize the azimuth, elevation, fuse setting and firing mechanisms.

With foregoing and other objects in view, my invention resides in the novel arrangement and combination of parts and in the 30 details of construction hereinafter described and claimed, it being understood that changes in the precise embodiment of the invention herein disclosed may be made within the scope of what is claimed without departing 35 from the spirit of the invention.

A practical embodiment of the invention is illustrated in the accompanying drawings, wherein:

Fig. 1 is a view in side elevation of a 40 gun showing the application of the fire control system;

Fig. 2 is a more or less diagrammatic view illustrating the synchronization of the various mechanisms; and

Fig. 3 is a sectional view on the line 3—3 of Fig. 1.

Referring to the drawings by numerals of reference:

There is shown in Fig. 1 a typical anti-aircraft gun consisting of a top carriage 5 rotatable on the base 6 by means of a traversing mechanism 7. A cradle 8 trunnioned in the top carriage and mounting the gun barrel 9 is provided with a segmental rack 10 engageable by the elevating mechanism 11.

A fuse setting mechanism 12 arranged to set the fuse of a round loaded in the gun, as described in the patent previously referred to, is mounted on the cradle, but in certain types of guns it may be mounted on the barrel itself. For convenience of illustration all of these mechanisms are shown on the same side of the gun, although in actual practice the traversing mechanism would be on the opposite side.

Referring to the diagrammatic view of Fig. 2 the means for indicating the amount of movement to be imparted to the traversing, elevating, and fuse setting mechanisms are identical and each consist of a pair of concentric wheels, the outer wheel 13 geared to one of the mechanisms 7, 11, and 12 at the gun and the inner wheel 14 under remote control receiving its movement direct from the computing instrument at the battery commander's station and displaceable in an amount proportional to the desired function of either lateral deflection correction, vertical deflection correction or fuse reading. Each of the wheels is provided with an arrow or pointer 15 and when the outer wheel is moved to position its arrow in alinement with the arrow on the inner wheel, the function required to lay the gun or set the fuse will be applied to the corresponding mechanism. Both the outer and inner wheels carry insulated contact elements 13^a and 14^a arranged to be in engagement when the arrows register. The contact elements of the azimuth, elevation, and fuse setter mechanisms and also an insulated pin 16 in the breech block which contacts with the primer of the round when the breech block is closed are connected in circuit by the lead wires 17—17. In this way the round can only be fired when all data which enters into the determination of the predicted future position of the target is correctly applied to the gun and fuse.

In order that the gun commander may control the firing, a switch 18 is interposed in the electrical circuit so that he may at will open the circuit, for example, when a friendly plane is too close to the enemy plane. During such interruption data is being continuously transmitted and applied and firing may be resumed at any instant by merely turning the switch to close the circuit.

I claim:

1. In a gun including an electrically operated firing device, means for traversing the gun, means for elevating the gun, means for setting the fuse of a round within the gun, an index associated with each of said means, a member associated with each index and movable proportionate to data to be applied, electrical connections establishing a circuit between the firing device, the indexes and the members and a switch in said circuit.
2. In a gun including an electrically op-

erated firing device, means for traversing the gun, means for elevating the gun, means for setting the fuse of a round within the gun, an index associated with each of said means, a member associated with each index and movable proportionate to data to be applied, and electrical connections establishing a circuit between the firing device, and the indexes and the members. 15

JAMES C. KARNES.
